UNITED STATES PATENT OFFICE.

JAMES W. KENNEDY, OF CANTON, OHIO.

CROSSING SIGNAL.

Application filed August 13, 1923. Serial No. 657,049.

My invention relates to new and useful improvements in crossing signals and may be employed in connection with highway or railway intersections. The object of my invention is to provide a signal of this class the mechanism of which is water tight and will not be affected by the weather, thus prolonging the wear of the device and insuring its proper operation.

Another object is to provide a signal which will remain in operation until a vehicle has time to safely pass the crossing and then automatically cease to function.

The majority of crossing signals are in the form of signs and are situated in such a position that they do not warn the driver of a vehicle that he is approaching a crossing, in time to stop. To correct this defect I provide a signal in the form of a human figure which will operate and warn the driver of danger at a distance from the crossing, sufficient to enable him to slow down before reaching the same.

A still further object of my invention is to provide a signal which is operated by the vehicle itself as it approaches a crossing.

With the above and other objects in view which will appear as the description proceeds, my invention consists in the novel features herein set forth, illustrated in the accompanying drawings and more particularly pointed out in the appended claim.

In the drawings;

Fig. 1 is a view looking down on my device, showing the signal at two intersecting streets, and the vehicle operated means for actuating the same.

Fig. 2 is an enlarged view of my signal, showing the lights and stop sign secured to a figure in the form of a human being.

Fig. 3 is a view taken on line 3-3 of Fig. 2.

Fig. 4 is an enlarged view looking down on the signal operating means.

Fig. 5 is a detail view in section of the vehicle operated road switch or circuit closing device.

Fig. 6 is a cross sectional view from another point, of Fig. 5, and

Fig. 7 is a detail diagrammatic view of the mechanism and wiring of the signal itself.

The numeral 1 designates the road circuit closing device which is secured in a recess in the road, and enclosed in a container 2, preferably composed of sheet steel which is

provided with flanges 3. These flanges extend over the surface of the road for a distance sufficient to allow for the road to expand and contract without leaving a space 60 along the sides of the container. 4 designates a plate preferably brass, which is crimped to the container thus rendering it water tight.

Depression disks 5 are composed of a hard durable metal, and are provided with reduced threaded portions 6 which pass through the holes 7 in the plate 4 and engage the threaded apertures 8 in contact pins 9. Between the contact pins and the plate 70 4, I provide the insulation 14 which may be composed of any suitable resilient material.

At the bottom of the casing 1, I provide a rubber packing 10 which supports a copper screen 11.

The screen 11 and the plate 4 are provided with electrical connections 12 which lead to the signal through the conduit 13, and by depressing the contact pins 9 a circuit is made.

In the space between the plate 4 and the screen 11, I provide a packing 16, of soft rubber or other suitable material which will give and allow the pins 9 to contact with the copper screen 11. As a filling for the spaces 85 between the heads of the contact points, I use strips 15 of cork or other similar material.

At 48, I have shown an electrical signal operating mechanism which comprises magnetic coils 17 of the usual type, which when the circuit 18 is closed, will actuate the pivoted arm 19, the arm being held out of operation by a spring 27. This arm is connected at one end to the pivoted arm 20 by means 90 of a cross bar 21. The other end of said arm 20 is bent in substantially a hook shape 20' adapted to engage the rotatably mounted roller 28 on the disk 22 and oscillate said disk. Keyed to the center of the disk 22, 100 is a rotating hollow rod 29 which extends through the body portion of the human figure 34, and is secured by the bearing 35. The other end of said rod is secured to and operates a "stop" signal 30 provided with 105 a plurality of lights 31, the operation of which is described in my former Patent No. 1,421,251 of 1922. The "stop" signal is pivoted at 32 and secured in place by the rod 33.

At the same time the arm 20 actuates the 110 disk 22 and the "stop" signal, it pulls back the piston 36 by means of the jointed rods

37, thus forcing the oil or other suitable fluid up into the reservoir 38 through the apertures 39 of the ball valve 40. When the oil leaves the reservoir 41, the float 42 descends bringing the metal disk 43 in contact with the breaker points 44, thus completing a circuit with the battery 45 and energizing the coil 25. This in turn draws the rocker arm 24 down closing the circuit 46 which controls the lights 31 and 31'.

At the other end of the rocker arm 24, I provide an upwardly projecting finger 23, which when the arm is drawn down in contact with the core of the coil 25, engages the recess 22' of the disk 22 and locks the mechanism of the "stop" signal.

After the oil has run back through the delay element or valve 40, it raises the float 42 and breaks the circuit at 44, de-energizing the coil 25 and allowing the spring 26 to draw the arm back into normal position, at the same time breaking the light circuit 46. This also releases the finger 23 from the recess 22' of the disk 22, thus allowing the counter weight 47 to restore the stop signal 30 to a non-indicating position.

The road circuit closing means is situated in street X at a greater distance from the intersection of the two streets, than the circuit closing means in street Y as the vehicle approaching the crossing on street X has the right of way. By placing the circuit closing means in this manner the vehicle on street X operates the signal first thus warning the driver on road Y of his approach.

If the vehicle on street Y operates the signal before the vehicle on street X reaches the same, it will warn the latter in time for him to reduce his speed.

The operation of my device is obvious.

A vehicle passing over the road circuit closer 1, will depress the disks 5 and with them the plate 4 which will bring the pins 9 in contact with the screen 11. This will close the circuit 18 which will actuate the arms 19 and 20. By this movement the disk 22 is turned and with it the "stop" signal 30. At the same time the suction of the piston 36 will lower the float 42 and close the circuit at 44 which energizes the coil 25 drawing down the arm 24, closing the light circuit 46 and locking the disk 22 at 22'.

After the vehicle has had time to safely pass the crossing, the oil will have run back through the valve 40 and forced the float 42 upwardly breaking the circuit at 44, which will release the lock 22' and allow the signal to fall back to a non-indicating position, at the same time shutting off the lights 31 and 31'.

What I claim and desire to secure by Letters Patent is:—

In a signaling device for street intersections, a signal, a lamp, means for moving said signal from non-signaling position to signaling position, including a magnet, vehicle operated means for energizing said magnet on the approach of a vehicle, to the intersection, latch means for retaining said signal in signaling position and for energizing said lamp, a magnet for maintaining said latch in operative position, a circuit for said magnet, means including a dash pot actuated by said signal operating means to close the circuit to said last mentioned magnet for delaying the release of said latch for a predetermined time after the operation of said signal.

In testimony whereof I affix my signature.

JAMES W. KENNEDY.
